ENCASING MEANS FOR FURNACES

John J. Hricko, Stamford, Pa.

Application February 21, 1947, Serial No. 730,171

1 Claim. (Cl. 110—1)

1

This invention relates to encasing means for furnaces, and has for one of its objects the production of a simple and efficient means for obtaining quick and steady heat from a furnace and to obtain a maximum amount of heat for a maximum length of time in proportion to the fuel consumed by the furnace.

A further object of this invention is the production of a simple and efficient encasing means for hot air furnaces and the like, wherein the encasing means comprises a series of spaced bricks or blocks, to provide air spaces between the bricks or blocks and thereby obtain maximum heating results.

Other objects and advantages of this invention will appear throughout the following specification and claim.

In the drawing:

Figure 1 is a top plan view of the furnace, certain parts of the encasing means being broken away and the top or cap of the furnace being removed to illustrate the spaced arrangement of the bricks;

Figure 2 is a side elevational view of the furnace and encasing means;

Figure 3 is an enlarged fragmentary top plan view of a portion of the encasing means, a portion of the furnace wall being shown in section.

By referring to the drawing, in detail, it will be seen that 10 designates a conventional hot air furnace which may be of any type of construction without departing from the spirit of the invention. The furnace 10 is provided with the conventional damper and draft regulator 11 which may be of any suitable type. The furnace 10 is preferably provided with a forwardly protruding portion 12, the sides of which preferably diverge, as at 13, to conform to the ends of the bricks or blocks described in the following, and which provide the furnace encasing means. The protruding portion 12 is provided with a suitable fuel door 14, a suitable water pot 15 and an ash pit door 16, in the front face thereof, all of the conventional type, to facilitate servicing of the furnace conveniently from the front thereof.

In carrying out my invention, the furnace 10 is placed upon a suitable base 17 which is of suitable size to support the furnace 10 and also to support the encasing means 18. The encasing means 18 comprises a series of layers of bricks or blocks 19. The bricks or blocks 19 are placed in layers one upon the other, the individual bricks or blocks 19 of one layer being arranged in staggered relation to the bricks or blocks of the adjacent layer. The layers of bricks are held to-

gether by mortar or other plastic material 20 along their horizontal upper and lower edges, as shown in Figure 2.

It should be noted, however, that the individual bricks or blocks 19 are spaced from each other at their ends to provide radiating air spaces 21 between the various bricks or blocks of each layer of bricks or blocks. The furnace 10 is provided with a dome-shaped top or cap 22 which preferably overhangs or fits snugly over the top layer of bricks or blocks 19, for decorative purposes, as shown in Figure 2. Suitable pipes 23 pass through the top or cap 22 from the furnace 10 and extend to suitable locations for delivering heat from the furnace to desired areas, in the conventional manner common to such furnaces.

The bricks or blocks 19 which form the encasing means are placed tightly against the exterior of the furnace 10, and the air spaces between the bricks or blocks 19 will permit the bricks 19 at the ends thereof to absorb heat from the furnace, thereby providing quick, long, steady and a maximum amount of heat in proportion to the fuel consumed. The air spaces or air pockets 21 particularly provide a quick heat from the furnace, when needed so that immediate benefit may be obtained when the fire is started, through the compound benefit of the multiple air spaces 21.

It should be noted that there is no air circulation from one pocket to the other, and that the air entering the pockets between the bricks or blocks will become heated, and although air may be dissipated to the atmosphere surrounding the casing to heat the area surrounding the furnace, the heat from the furnace will heat the ends of the bricks or blocks and pass out through the air pockets or escape-ways 21 between the bricks.

It should be understood that the bricks or blocks 19 may be of any suitable design or type without departing from the spirit of the invention, but these bricks or blocks 19 are preferably concave on their inner faces 24 so as to snugly fit and conform to the contour of the outer face of the furnace. Furthermore, the air spaces or pockets 21 extend from the outer face of the furnace 10 to the outer face of the blocks 19 to provide a maximum surface area for each block for the absorption of a maximum amount of heat. From the foregoing description, it will be noted that the present invention relates to the construction of the encasing means, whereby the air spaces 19 are provided and it is not desired to limit the invention to a particular type of furnace with which the encasing means is used.

It should be noted that the inner face of each

brick 19 fits in contacting relation with the wall 10^a of the furnace 10, throughout the entire length of each brick. Since the bricks contact the furnace wall and are spaced from each other at their ends, the bricks will be efficiently and quickly heated along their inner faces because of the contact with the furnace wall, and the heat from the spaced ends of the bricks will heat the air which is within the air-escape-ways or air spaces 21. The air-escape-ways communicate directly with the outside atmosphere.

Having described the invention, what I claim as new is:

In combination with a furnace of the conventional type, an encasing means formed of a plurality of layers of bricks encircling the furnace from bottom to the top thereof, each layer of bricks consisting of a plurality of bricks laid end-to-end in spaced relation to provide air-escape-ways extending from the outer wall of the furnace to the exterior of the bricks and between the bricks, the air-escape-ways communicating at their outer ends with the outside atmosphere which surrounds the furnace, the inner face of each brick fitting in contacting relation through-

out its entire length with the wall of the furnace, and the air-escape-ways between the bricks of one layer extending in vertical staggered relation relative to the air-escape-ways between the bricks of the adjoining layers, the ends of the bricks being adapted to heat the air in the escape-ways as the air passes between the bricks and to thereby also heat the area surrounding the furnace as the air escapes from between the bricks.

JOHN J. HRICKO.
